PIPE HEATER

George W. Watts, Whiting, Ind., assignor to
Standard Oil Company, Chicago, Ill., a corpora-
tion of Indiana

Application June 11, 1934, Serial No. 729,986

10 Claims. (Cl. 196—116)

This invention relates to improvements in pipe heaters and more particularly to pipe heaters used in distilling petroleum oils.

An object of my invention is to provide an improved pipe heater in which is attained automatic and independent regulation of the temperatures of the oil being heated. A further object is the attainment of regulation of the heat input into the convection tubes. A still further object is the provision of an improved pipe heater or tube still useful in combination atmospheric and vacuum distillation units. A further object is the provision of means whereby the heat input in the convection section of a pipe heater is controlled in response to the temperature of the oil being heated in one or more banks of convection tubes. Other objects will appear as this description proceeds.

In the drawings which form part of the specification Figure 1 is a sectional view of a heater and fractionating columns constructed in accordance with my invention;

Figure 2 is a view similar to Figure 1 of another form of the heater;

Figure 3 is a sectional view along the line III—III of Figure 1;

Figure 4 is a detailed view of a bridge wall and modification of the control dampers which form part of my invention;

Figure 5 is a detailed view similar to Figure 4 of a modified type of damper;

Figures 6 and 7 are detailed views of additional modifications of the damper; and

Figures 8, 9 and 10 are modifications of the arrangement shown in Figure 1.

In Figure 1, I have illustrated a conventional type of heater or pipe still with a housing 2, a combustion chamber 3, and a convection section 4. The combustion chamber and convection sections 40 are separated by a bridge or rear wall 5 which extends between opposite side walls of the housing and from the floor to a point adjacent the roof 6 of the housing. A flue 7 connected with a stack (not shown) communicates with the convection section 4 at the lower end thereof.

Fuel is introduced for the purpose of combustion into the combustion chamber through nozzles or burners 8 which are preferably mounted on the lower part of the forward wall of the housing 50 but which may have any other suitable location. The hot products of combustion introduced into or generated in the combustion chamber 3 tend to flow upwardly in the combustion chamber, thence over the bridge wall 5, and thence downwardly through the convection section 4. The

tubes in the convection section are preferably disposed in a plurality of superimposed banks (shown in Figure 1 as banks 9 and 10). The bridge wall is pierced with one or more ports 40 which are located at an intermediate part of the bridge wall. One bank of convection tubes 10 is disposed above the level of the ports 40 and another bank of convection tubes 9 is disposed below the level of the ports 40.

In the modification shown in Figure 1, relatively cool oil is introduced into the lower bank of convection tubes 9, is partially heated therein and thence discharged through the line 10 into a fractionating column 12 wherein the vaporized oil is carried off overhead and the unvaporized oil together with any condensate is discharged from the bottom of the column through line 13, and thence introduced for further heating in the pipe heater. I prefer the arrangement shown in Figure 1, in which the unvaporized oil and condensate in line 13 is introduced into tubes disposed in the combustion chamber. In Figure 1 the oil is passed through rear wall tubes 14, thence front or bridge wall tubes 14a, thence roof tubes 14b, thence rear wall tubes 14c, and finally into the upper bank of convection tubes 10, from which the heated oil is discharged through line 15 into the second fractionating column, 16. The precise arrangement of tubes in the combustion chamber may be modified to suit the desires of the designer. Thus, for example, floor tubes may be provided in the combustion chamber and the routing of oil through the floor tubes, wall tubes and roof tubes may be varied at will.

The discharge line 11 may be provided with a thermostatic control element or sylphon 22 which serves to regulate the fuel supplied for combustion through the control valve 19. This thermostat 22 is preferably located on the discharge end of the lower or preheating convection bank 9.

The ports 40 are provided with dampers or control elements 17. In Figure 1 these are shown as being disposed for horizontal movement. The dampers 17 are placed in recesses 21. These dampers or port closures are connected to a control unit 20 which may be of the solenoid type or any equivalent type and which in turn is directly connected to a thermostatic control 18 placed preferably on the line 15 at the discharge end of the upper bank of convection tubes 10.

In Figure 1, I have shown two fractionating towers, 12 and 16, which preferably may be atmospheric and vacuum columns respectively.

In the modification illustrated in Figure 2 (in

which the elements bear the same reference numerals as the corresponding elements in Figure 1, the arrangement of the housing combustion chamber and convection section is generally similar to that of Figure 1. I have shown, however, three banks of tubes in the convection section and have shown a slightly different arrangement of tubes in the combustion chamber. As stated before, however, the arrangement of tubes in the combustion chamber may be varied at the will of the designer. The bridge wall I have shown pierced by two sets of superimposed ports, an upper series of ports 40 and a lower series of ports 40a, each series of ports being provided 10 with closures 17 and 17a respectively arranged generally similarly to the closures described in Figure 1.

In this modification the relatively cool fresh feed is introduced into the lowermost bank of 20 convection tubes 23, is passed therethrough and thence discharged through line 24 which conveys the preheated oil into the bridge wall tubes 25, thence through the front wall tubes 25a, and thence through the upper bank of roof tubes 25b. The oil discharged from the roof tubes is conveyed through line 26 into the bank of convection tubes 8, from which it is discharged through line 11 into a fractionating column (not shown). The unvaporized oil plus condensate 30 from this fractionating column, which is preferably maintained under atmospheric pressure, is discharged from the bottom of the column through a line 13, then introduced into the combustion chamber wherein it is heated in bridge wall tubes 14, front wall tubes 14a, and then through roof tubes 14b, from which it is conveyed through line 26a, to the upper bank of convection tubes 10. The heated oil discharged from the upper bank of convection tubes 10 is 40 conveyed through line 15 to a second fractionating column (not shown) which is preferably maintained under vacuum.

The lowermost bank of convection tubes 23 is preferably disposed below the level of the lowermost ports 40a. The intermediate bank of convection tubes 8 is preferably disposed below the level of the uppermost ports 40 and the upper bank of convection tubes 10 is disposed above the level of the upper ports 40. 50 The discharge line 24 is provided with a control element 22, preferably thermostatic or of the sylphon type, which acts through control valve 19 to regulate the amount of fuel introduced into the combustion chamber through the nozzles 8. The ports 40 are provided with closures or dampers 17 disposed in recesses 21 similarly to the ports in Figure 1, and these closures or dampers are controlled through controls 20 and 20a which are responsive to the temperature of the oil, preferably the temperature at the discharge end of the convection bank 10. The thermostat 18 disposed on the discharge line 15, or equivalent element operates to control the control unit 20. The lower bank of ports 40a 60 is similarly equipped with closures 17a which are in turn controlled through a control element 20a which is responsive to the temperature of the oil being discharged from the convection bank 8 as that oil affects the thermostatic or equivalent element 18a.

In Figure 4, I have disclosed a detailed drawing in section of a modified type of damper or port closure. In this modification the closures 75 27 are disposed on the convection side of the

bridge wall and are arranged for horizontal movement, being supported by brackets 28.

In the modification shown in Figure 5 the closures are of a slightly different type, being elements 29 which are disposed in recesses 30 built into the bridge wall and in which the closures or dampers move upwardly or downwardly to vary the effective area of the port. 5

In Figure 6 the damper or closure 31 is of the usual butterfly type arranged to revolve about a fixed axis in order to vary the effective area of the port.

In Figure 7, I have shown the closure or damper as a plate 32 hinged on the support 33 which is located on the convection side of the bridge 15 wall.

In Figure 8, I have shown the modification of a heater similar to the heater disclosed in Figure 1. In this modification the upper coil of tubes in the convection section (the coil being 20 designated "B") is smaller than the bank of convection tubes disclosed in the lower part of the convection section and designated "A". The convection tubes A may be connected in any suitable manner with any arrangement of 25 tubes in the radiant section of the furnace.

In Figure 9, I have shown a modification generally similar to Figures 1 and 8. In this modification the convection bank of tubes B is relatively large and the convection bank of tubes A 30 is relatively small. In each of the modifications shown in Figures 8 and 9 the temperature of the oil discharged from the upper bank B operates to control the damper or closure 17 and the oil discharged from the lower bank of convection tubes A operates to control the fuel introduced through the nozzle 8. 35

In Figure 10, I have shown a modification in which both convection sections B and A are relatively large. In this modification I have shown B as the lower bank of convection tubes, the temperature of the oil discharged from which controls the damper or closure 17. The oil discharged from the upper bank of convection tubes A operates to control the fuel introduced through the nozzle 8. 45

In each of the modifications above the damper or closure element is connected to and actuated by a control which is responsive to the temperature of the oil being heated and preferably the temperature of the oil in a bank of convection tubes disposed above the level of the ports. 50

The operation of the apparatus which I have described above with reference to Figure 1 is as follows: The fresh feed is introduced into the convection coil 9 where it is preheated and then discharged into the atmospheric tower 12 which may be any conventional type of fractionating column such as bubble tower, flash drum, packed or baffle tower. The vaporized portion of the preheated oil is separated from the unvaporized portion. The condensate together with any unvaporized oil is discharged through line 13 from the bottom of the tower 12 and then is passed to the tubes in the combustion chamber of the still and thence into the convection bank 10. The heated oil is led into the vacuum tower 16, which may be similar to the tower 12 or may be of any desired conventional type. 60

The preheated oil discharged from the convection bank 9 serves to regulate the amount of fuel introduced into the combustion chamber. This regulation is maintained by means of a thermostatic or sylphon control 22, which is re- 70

sponsive to the temperature of the preheated oil discharged from the convection bank 9 and which operates upon the control valve 19. If the temperature of the oil discharged from the convection bank 9 rises above a desired point, the thermostat 22 and control valve 19 tend to diminish the amount of fuel introduced into the combustion chamber. Conversely, if the temperature of the oil discharged from bank 9 drops below a desired point, the control valve 19 is automatically opened to admit fuel into the combustion chamber.

In the conventional bridge wall furnace hot gases or products of combustion which are introduced into the combustion zone tend to flow upwardly in the combustion zone and thence over the top of the bridge wall and downwardly through the convection zone from which the hot gases are discharged into a stack. In this conventional type of bridge wall furnace the convection tubes at the uppermost part of the convection zone tend to become more severely punished with resultant deterioration of the tubes themselves and coking of the oil within the tubes—that is, of course, relative to the convection tubes in the lower part of the convection zone. This punishment of the upper convection tubes is due to several factors such as radiant heat which is re-radiated from the roof of the furnace. It is also due to the fact that immediately after being discharged from the combustion zone the hot gases are relatively hotter than they are after have been cooled by contact with a plurality of tubes in the convection zone. In the conventional bridge wall furnace it is sometimes difficult to get a balanced heating of the convection tubes for this reason.

To operate my heater in the most flexible fashion I have provided means for varying the amount of hot products of combustion so bypassed into the convection zone. These means comprise closures or dampers adapted to vary the effective area of the ports and at the same time to control the amount of gases permitted to flow through the ports. In order to get satisfactory regulation of the amount of gases so bypassed I control the dampers or closures through a control element 20 which may be a solenoid or any equivalent structure which in turn is responsive to the temperature of the oil being discharged from the upper bank of convection tubes 10. Thus, as the oil being heated in the upper bank of convection tubes 10 tends to be overheated or too hot, the temperature of the thermostat 18 rises. The thermostat acts upon the control 20 to open the damper or closure 17, permitting more hot gases to flow through the port and coincidentally diminishing the amount of gases which flows over the bridge wall and down through the convection tubes 10. This will tend to decrease the temperature of the oil being heated in the convection tubes 10. Conversely, when the temperature of the oil being heated in convection tube 10 sinks below a desired point the temperature of the oil acts upon the thermostat 18 which in turn operates upon the control 20 to close the ports and lessen the effective area thereof. This results in diminishing the amount of gas which is bypassed through the ports and coincidentally increasing the amount of gas which must flow upwardly over the bridge wall and down through the convection tubes 10. The amount of heat imparted to the convection tubes 10 and to the oil being heated therein is thus controlled within desired limits.

Furthermore, in the case where the ports 40 are relatively wide open, permitting a very appreciable quantity of hot gases to flow through the convection bank 9, there is at times a tendency to overheat the tubes in this convection bank 9. Where this overheating is experienced the thermostat 22 acting upon the control valve 19 operates to diminish the total quantity of fuel and the total quantity of hot products of combustion introduced into the combustion chamber. Thus the operation of the heater in toto is effectively regulated within desired limits.

In the modification shown in Figure 2 the operation of the heater is substantially the same in principle. In this modification I have shown three banks of convection tubes and two series of ports. The lowermost bank of convection tubes is a preheater bank 23 which corresponds to the bank 9 in Figure 1. The temperature of the oil discharged from this preheater bank serves to control and regulate the amount of fuel introduced into the combustion chamber. The effective area of the ports 40 is controlled by means of dampers or closures which are responsive to the temperature of the oil being discharged from the convection bank 10, while the effective area of the ports 40a is controlled by dampers or closures which are in turn controlled by the temperature of the oil discharged from the convection bank 9.

In this modification when the oil in tubes 10 becomes overheated the thermostat 18 operates to open the damper 17 and enlarge the effective area of the ports 40. Similarly, where the temperature of the oil being heated in the bank 9 tends to rise to too great a degree, the thermostat 18a operating on the damper 17a tends to enlarge the effective area of the ports 40a, in either case permitting hot gases to by-pass the bank of tubes immediately above the ports. It is obvious that where the temperature of the oil discharged from lines 15 and 11 drops below a desired point, the dampers are automatically closed, thus eliminating the by-pass (in part at least) and permitting more hot gases to contact the bank of tubes immediately above the ports.

If the B coil is relatively small, as compared with the A coil in the convection bank, as shown in Figure 8, the preferred arrangement will be to place the B coil in the upper part of the convection section. The A coil may well consist of two sections; one located below the B coil in the convection section and the other in the radiant section, or the coil may be divided as shown in Figure 2. The B coil controls the setting of the damper and the A coil controls the firing valves. The B coil would be of such a size that the outlet temperature from B would be too high when all of the hot gases were passed through B and the firing was at the same time controlled to give the proper A temperature. The effect of the damper control as controlled by B would be to pinch down on the amount of gas passed through B until the proper B temperature was secured. At the same time the A control would regulate the fire to keep the desired A outlet temperature. Obviously the unit would not function so well if the B coil were placed at the bottom of the convection section, for then it would be necessary to pass all of the hot gases through this coil. In this event the control would be secured through a regulation of the temperature of the gas and this would not be as effective as a regulation of the volume of the gas. With this arrangement the B coil would have to be made so that there

would be insufficient heat pickup by it when all of the gas was sent through the convective part of the A coil. Then some gas would be bypassed around the A coil to increase the average temperature of the gas passing through the B coil. This, in turn, would drop the A temperature and would require more firing. For these reasons it is preferable to place the smaller B coil in the upper part of the convection section. It may also be observed that if both the A and B convection coils are small it is much better to place the B coil at the top of the convection section, for if it were placed at the bottom little control could be obtained through varying the amount of gas which goes through the A coil since a small A coil would not remove much heat.

In the modification illustrated in Figure 9 the B coil is relatively large and the A coil is relatively small. If the B coil were placed at the bottom bypassing of gas around A would have little effect on either A or B, therefore the control would not be sensitive. However, if the B coil were placed at the top of the convection section the bypassing of gas around it would be very effective in controlling the B outlet temperature, but would not have much effect on the A outlet temperature. Consequently, with the B coil controlling the temperature and the A coil controlling the firing, the regulation is very sensitive and quite flexible.

If, as illustrated in Figure 10, both convection coils are relatively large, either may be placed at the top or bottom of the convection section and good regulation will be secured in either case. If, for example, the A coil is placed on top and the B coil below sensitive regulation is obtained if the B coil controls the gas by-pass and the A coil controls the firing. With this arrangement, if the gas which is left to pass through A is not in sufficient quantity or at the proper temperature to give the desired A outlet temperature, then the fuel will be increased and this will result in an increase in the amount and temperature of the gas bypassed directly through the B coils. As a result, the damper will partially close to get the required B condition and the A coil will receive more gas at a higher temperature. Through the interaction of the temperature and fuel control the proper conditions of heating A and B may be readily obtained. On the other hand, if the B coil is placed on top the amount of gas passed through B will be regulated to give the proper temperature to B. If this results in too low a temperature for A the fuel will be increased to get the A requirements and since this in turn will tend to increase the B temperature the damper will open and bypass gas around B. Again the regulation will be satisfactory for both coils.

In the modifications shown in Figures 1, 2, 8, 9, and 10, I have disclosed the oil flowing from the top to the bottom of each of the coils in the convection section, that is, in a direction concurrent with the flow of the gases through the convection section. This would be advantageous where the convection tubes functioned as soaking or digester coils in a cracking still. It is within the scope of my invention, however, to reverse the flow of the oil in one or more or all of the banks of convection tubes, thus employing countercurrent flow of oil with respect to the gases.

My invention possesses the advantages of flexibility and accurate control so that when given operating conditions are established they may be maintained without upsetting the balance of the

furnace. It will be apparent that efficient operation of my furnace is obtained regardless of whether the convection tubes 10 are larger or smaller or the same size as the convection tubes 9 disposed below them. This is an advantage which is not found in the ordinary type of bridge wall heater, and I contemplate as part of my invention the use of banks of convection tubes composed of tubes which may be larger or smaller than the tubes in the other banks in the convection zone.

My furnace is particularly suited to the heating of two or more oil streams undergoing cracking. For example, I may heat a gas oil stream to a temperature of 900 to 975° F. in one coil and a heavy naphtha stream in another coil to a temperature of 985° to 1100° F. for reforming. Still other streams, such as heavy residuum, cycle gas oil, virgin gas oil, etc., may be heated to other temperatures.

It will be understood that whereas the foregoing is a full and complete description of my invention, I am not limited therein except as expressed in the claims as follows.

I claim:

1. In a heater for fluids, a combustion chamber, a convection chamber, a bridge wall having ports therein interposed between said chambers, means for introducing hot products of combustion into said combustion chamber, means for causing the hot products of combustion to tend to flow upwardly in said combustion chamber, thence over said bridge wall and through the ports therein and thence downwardly through said convection chamber, fluid-confining tubes in said combustion chamber and adapted to be heated by said hot products of combustion, an upper bank of fluid-confining tubes disposed above said ports and in said convection chamber, a lower bank of fluid-confining tubes disposed below said ports and in said convection chamber, controlled dampers for varying the area of said ports and at the same time varying the amount of hot products of combustion passed over said bridge wall and thence in contact with said upper bank of tubes, thermostatic means responsive to the temperature of the fluid at the discharge end of said lower bank of tubes for controlling said dampers and said port areas, and means responsive to the temperature of the fluid at the discharge end of said upper bank of tubes for controlling the means for introducing hot products of combustion into said combustion chamber.

2. In a heater for fluids, a combustion chamber, a convection chamber, a bridge wall interposed between said chambers, means for introducing hot products of combustion into said combustion chamber, fluid-confining tubes in said combustion chamber disposed to receive heat from substantially all of the products of combustion, banks of fluid-confining tubes in said convection chamber for conducting separate streams of fluid therethrough, means for connecting at least a part of the tubes in said combustion chamber to one of the banks of tubes in the convection chamber, a damper arrangement disposed within said bridge wall for by-passing a portion of the hot products of combustion around one of the banks of tubes in the convection chamber, means connected to the discharge end of one of the banks of tubes in the convection chamber responsive to the temperature of the stream of fluid passing therethrough for controlling the damper arrangement and regulating the quantity of hot products of combustion by-passed around

one of the banks of tubes in the convection chamber and other means connected to the discharge end of another of the banks of tubes in the convection chamber responsive to the temperature of another separate stream of fluid passing therethrough for simultaneously controlling the means for introducing the hot products of combustion into said combustion zone.

3. In a heater for fluids, a combustion chamber, a convection chamber, a bridge wall interposed between said chambers, means for introducing hot products of combustion into said combustion chamber, fluid-confining tubes in said combustion chamber disposed to receive heat from substantially all of the products of combustion, banks of fluid-confining tubes in said convection chamber for conducting separate streams of fluid therethrough, means for connecting at least a part of the tubes in said combustion chamber to one of the banks of tubes in the convection chamber, a damper arrangement disposed within said bridge wall at a point lower than at least one of the banks of tubes in the convection chamber for passing a portion of the hot products of combustion therethrough without substantially contacting the bank of tubes in the convection section above said damper arrangement, means connected to the discharge end of the bank of tubes above said damper arrangement in the convection section responsive to the temperature of the stream of fluid passing therethrough for controlling the damper arrangement and regulating the quantity of hot products of combustion passed therethrough and other means connected to the discharge end of another of the banks of tubes in the convection chamber below said damper arrangement responsive to the temperature of another stream of fluid passing therethrough for simultaneously controlling the means for introducing the hot products of combustion into said combustion chamber.

4. The method of heating petroleum oil in an apparatus having a combustion chamber and a convection chamber which comprises flowing combustion gases through said combustion chamber, heating one stream of oil passing through said combustion chamber by substantially all of said combustion gases, conducting said stream of oil through a part of said convection chamber heated by only a part of the combustion gases, conducting another part of the combustion gases to another part of the convection chamber, regulating the quantity of combustion gases heating the aforementioned stream in response to the outlet temperature thereof, passing another stream of oil through the convection heating chamber, heating it by all of the combustion gases and regulating the quantity of combustion gases flowing through said combustion chamber in response to the temperature of the last mentioned stream of oil leaving the convection chamber.

5. The method of heating petroleum oil in an apparatus having a combustion chamber and a convection chamber which comprises flowing combustion gases through said combustion chamber, heating one stream of oil passing through said combustion chamber by substantially all of said combustion gases, conducting said stream of oil through the upper part of said convection chamber, heating said stream of oil by only a part of the combustion gases, conducting another part of the combustion gases to a part of said convection chamber below the aforementioned stream, regulating the quantity of combustion

gases heating the aforementioned stream in response to the outlet temperature thereof, passing another stream of oil through the lower part of said convection chamber and heating it by all of the combustion gases and regulating the quantity of combustion gases flowing through said convection chamber in response to the temperature of the last mentioned stream of oil leaving the convection chamber.

6. In a heater for fluids, a combustion chamber, a convection chamber, a bridge wall having ports therein interposed between said chambers, means for introducing hot products of combustion into said combustion chamber, means for causing part of the hot products of combustion to flow over said bridge wall and another part through the ports therein and thence downwardly through said convection chamber, fluid-confining tubes in said combustion chamber and adapted to be heated by substantially all of said hot products of combustion, an upper bank of fluid-confining tubes disposed above said ports and in said convection chamber, a lower bank of fluid-confining tubes disposed below said ports and in said convection chamber, controlled dampers for varying the area of said ports to vary the amount of hot products of combustion passed therethrough and at the same time varying the amount of hot products of combustion passed over said bridge wall and thence in contact with said upper bank of tubes, thermostatic means responsive to the temperature of the fluid at the discharge end of said upper bank of tubes for controlling said dampers and said port areas, and means responsive to the temperature of the fluid at the discharge end of said lower bank of tubes for controlling the means for introducing hot products of combustion into said combustion chamber.

7. In a heater of the bridge wall type for heating petroleum oils, a combustion chamber, means for introducing hot products of combustion into said combustion chamber, oil-confining tubes in said combustion chamber, a convection chamber, superimposed banks of oil-confining tubes in said convection chamber and adapted to be heated by hot products of combustion discharged from said combustion chamber, a bridge wall having ports therein interposed between said combustion and said convection chambers, said ports providing means whereby at least part of the hot products of combustion are introduced into said convection chamber without passing over the bridge wall and whereby convection tubes located above said ports are by-passed by said hot products of combustion, means for controlling the effective area of said ports, to vary the amount of hot products of combustion passed therethrough, said means being responsive to the temperature of the oil at the discharge end of the bank of convection tubes located above said ports, and means responsive to the temperature of the oil in the convection tubes located below said ports for controlling the amount of hot products of combustion introduced into said combustion chamber.

8. A system for distilling petroleum oil comprising a heater of the bridge wall type, a first fractionating column, a second fractionating column, a combustion chamber in said heater, a convection chamber in said heater, a bridge wall having ports therein disposed between said combustion and said convection chambers, means for introducing hot products of combustion into said combustion chamber, means for conveying said hot products of combustion over said bridge

- wall and thence downwardly through said convection chamber, oil confining tubes in said combustion chamber, an upper bank of tubes in said convection chamber and disposed above the level 5 of said ports, a lower bank of tubes in said convection chamber and disposed below the level of said ports, means for causing oil to flow through said lower bank of tubes, thence to said first fractionating column wherein the vaporized oil 10 is fractionated from the unvaporized condensate, means for conveying said condensate as a separate stream to said combustion chamber for heating therein, means for conveying the heated oil from said combustion chamber to the upper bank of tubes in said convection chamber for further heating therein, means for conveying to said second fractionating column the oil discharged from said upper bank of tubes, dampers for said ports and means responsive to the temperature of the oil at the 15 discharge end of said upper bank of tubes for controlling the setting of said dampers to vary the amount of hot products of combustion passing through the ports and thus by-pass said upper bank of tubes. 15
10. In a heater for heating at least two separate streams of fluid, a combustion chamber, a convection chamber, a bridge wall having ports therein interposed between said chambers, means for introducing hot products of combustion into 20 said combustion chamber, means for causing the hot products of combustion to flow upwardly in said combustion chamber, thence over said bridge wall and through the ports therein and thence downwardly through said convection chamber, fluid-confining tubes in said combustion chamber and adapted to be heated by said hot products of combustion, a bank of fluid-confining tubes in said convection chamber and located above the level of said ports, another bank of 25 fluid-confining tubes in said convection chamber and located below the level of said ports, a connection for conducting fluid in series from said tubes in the combustion chamber to one of the said banks of tubes in the convection chamber, controlled dampers for varying the area of 30 said ports to vary the amount of hot products of combustion passed therethrough, and means responsive to the fluctuations produced in the temperature of the fluid flowing through said upper tubes for controlling the means for introducing hot products of combustion into said combustion chamber. 35
9. A system for distilling petroleum oil comprising a heater of the bridge wall type, a first fractionating column, a second fractionating column, a combustion chamber in said heater, a convection chamber in said heater, a bridge wall having ports therein disposed between said combustion and said convection chambers, means for introducing hot products of combustion into said combustion chamber, means for conveying said 40 hot products of combustion over said bridge wall and thence downwardly through said convection chamber, oil-confining tubes in said combustion chamber, an upper bank of tubes in said convection chamber and disposed above the level of said ports, a lower bank of tubes in said convection chamber and disposed below the level of said ports, means for causing oil to flow through said lower bank of tubes, thence to said first fractionating column wherein the vaporized oil 45 is fractionated from the unvaporized condensate,

GEORGE W. WATTS.
